ELECTRIC HEATER

Francis W. Perry, Dormont, Pa., assignor to
Edwin L. Wiegand, Pittsburgh, Pa.

Application September 22, 1938, Serial No. 231,185

20 Claims. (Cl. 219—37)

My invention relates to electric heaters in general, and more particularly to supporting means for one or more electrical heating elements. Electric heaters embodying my invention are particularly adapted for use in electric ranges. The principal object of my invention is to provide new and improved electric heaters of these types.

In the drawings accompanying this specification, and forming a part of this application, I have shown, for purposes of illustration several forms which my invention may assume, and in these drawings:

Figure 1 is a side elevation of an electric range unit embodying my invention.

Figure 2 is a bottom view of the range unit shown in Figure 1, but with the reflector and the means for connecting it to the range unit omitted, and a part shown fragmentarily,

Figure 3 is a fragmentary sectional view, on an enlarged scale, taken on the line 3—3 of Figure 2, looking in the direction of the arrows, but with the reflector and connecting means included,

Figure 4 is a fragmentary perspective view of disassembled details,

Figure 5 is a bottom view, similar to Figure 2, but of another embodiment of my invention,

Figures 6, 7, and 8 are fragmentary sectional views taken on the lines 6—6, 7—7, and 8—8 respectively, of Figure 5, looking in the direction of the arrows,

Figure 9 is a view similar to Figure 2, but of another embodiment of my invention, and

Figure 10 is a fragmentary sectional view taken along the line 10—10 of Figure 9, looking in the direction of the arrows.

Referring to Figures 1 through 4, the range unit 20 here shown comprises one or more electrical heating elements (here shown as two in number) 21, 22. The heating elements 21, 22 are in this instance of ring form, constructed and arranged so that they are concentric. The heating elements 21, 22 are here shown as supported from a stove top 23 by a supporting means which, in this instance, includes a support ring 24 resting on the stove top 23 having an aperture 26, and includes a support 27 which is here shown as supported by the support ring 24. The support 27 serves as a support for the heating elements 21, 22 as will hereinafter more fully appear. The range unit 20 also includes a reflector 28 disposed beneath and supported by the support 27.

The support 27, as here shown, is of cast metal and comprises three principal generally radial

arms 29, 30, 31, and two auxiliary arms 32, 33, integrally joined at their outer ends to a generally heart-shaped frame 34, and integrally joined at their inner ends to an arcuate portion 35. 5 Each of the principal arms, 29, 30, 31, is here shown as comprising a pair of generally radially spaced bushings 36, 37 of inverted cup-like form. Each bushing has an aperture 38 in the top thereof, these apertures being desirably slightly elongated in a generally radial direction, as may be best seen in Figure 4. Disposed in each pair of bushings 36, 37 is a lever or saddle 39, one of which may be seen in perspective in Figure 4, disassembled from the bushings 36, 37 there 10 shown. Inasmuch as the saddles 39 are all identical and each cooperates with its pair of bushings 36, 37 in the same way, a description of one will serve for all.

The saddle 39 comprises a flat central portion 20 40 adapted to be inserted in a slot 41 in the portion 42 joining the bushings 36, 37. The entrance portion of the slot 41 joins the two apertures 38 in the bushings 36, 37. The slot 41 is bridged transversely, below its entrance portion, by a V-shaped bridge or knife edge fulcrum 43, this fulcrum and the similar fulcrums (not visible) associated with the other sets of bushings 36, 37 in the arms 29, 31, being in this instance, each directly below a space 44 left between the heating elements 21, 22. The central portion 40 of the saddle is provided with a V-shaped notch 45, of larger angle than the V-shaped fulcrum 43, as may be best seen in Figure 3. At the 25 ends of the central portion 40 of the saddle there are provided tubular portions 46a, 46b, here shown as of elliptical or generally elongated cross-section. The lower ends 47 of the tubular portions 46a, 46b are here shown as generally 30 plane, whereas the upper ends are here shown as V-shaped, each upper end providing two fulcrums 48.

The heating elements 21, 22, are here shown as constructed and arranged in the following 35 manner, to cooperate with the saddles 39. The heating elements 21, 22 may be of any desired form; they are here shown as each comprising a metallic sheath 49 within which is disposed any desired form of resistor 50, here shown as 40 of the strip type. The resistor 50 may be embedded in refractory electrical-insulating heat-conducting material 51, and this material may be in the form of suitable granular, comminuted or powdered refractory material, preferably compacted to a dense hard condition. The heating

element 21 is here shown as provided with three studs or rivets 52, 53, 54, circumferentially so spaced that they are adapted to be inserted through the tubular portions 46b of the saddles 39; and the heating element 22 is shown as similarly provided with three studs or rivets 55, 56, 57, circumferentially so spaced that they may be inserted through the tubular portions 46a of the saddles 39, when the saddles are assembled with the support 27 as hereinbefore described. Each of the rivets, 52 through 57, has a head 58 within the sheath 49 of the respective heating element, the shanks of the rivets projecting downwardly, as viewed in Figure 3, through openings in bottom portions 59 of the respective sheaths. The rivet heads 58 may be disposed in recesses formed by bosses 60, and these bosses may be strengthened by ridges 61, embossed to a less degree than the bosses. Parts of the ridges 61 are visible in Figure 2. The shanks of the rivets extend downwardly through the tubular portions 46a, 46b of the saddles 39. The heating elements 21, 22 may be held assembled with the saddles 39 in any desired manner. To this end, the ends of the shanks of the rivets are here shown as bifurcated longitudinally, the ends 62 of the furcations being spread apart, and, in this instance, two washers 63, 64 are disposed, on each shank, between the surface 47 of the lower end of the respective tubular portion and the bent furcations 62 of the respective rivet shank. Desirably, a washer 65 may be interposed between each boss 60, and the fulcrums 48 provided at the upper ends of the tubular portions 46a, 46b, so that when the heating elements 21, 22 are assembled with the saddles 39, a boss 60 normally rests on a washer 65, and the washer rests on the fulcrums 48, as may be seen in Figure 3. The washers 65 may be of less diameter than the minor axis of the respective apertures 38. Downward movement of either one of the heating elements 21, 22, is stopped, after predetermined movement from the position shown in Figure 3, by engagement of an under surface of the heating element with a top surface of a respective one of the bosses 36, 37, in this instance by engagement of the ridges 61 with lugs 66 which may be provided on each of the bosses 36, 37.

In order to permit the freedom of movement necessary for the desired operation of the parts, the construction and arrangement is such that a desired space is left between the uppermost washer, 64, and the surface 47 of the lower end of the corresponding tubular portion.

The uppermost washers, 64, are here shown as of larger diameter than the minor axis of the apertures 38 in the bosses 36, 37, and under such conditions the heating elements 21, 22, and the saddles assembled therewith, while they may be lifted upwardly a predetermined amount, cannot be removed from the support 27 by such movement, since the washers 64 will abut the under sides of the tops of the bosses 36, 37.

The range unit 20 is desirably provided with the reflector 28 and this is here shown as having a principal portion 67 of generally conical form, the upper surface extending downwardly from the center of the reflector. The central portion of the reflector has a slightly downwardly dished portion 68 provided with an aperture 69. In the portion 67, near the junction between the portions 67, 68, are at least two circumferentially spaced apertures (one of which, 70, may be seen

in Figure 3) into which extend rounded projections 71 formed integrally on the support 27. These projections, 71, are here shown as provided on the arms 30, 31 of the support 27. The projections 71, in cooperation with the apertures 70, serve to locate the reflector 28 and hold it from circumferential movement, and the reflector is here shown as held in position against the support 27, by means of a bolt 72 and wing nut 73. The bolt is here shown as comprising a sheet metal head including a cup 74, the top of which is below the level of the upper surfaces of the heating elements 21, 22, and including also a cup 75 nested in the cup 74. Flanges 76, 77 of the cups 74, 75 are here shown as tapering downwardly and inwardly slightly so that the cups are firmly held together. The cup 75 has its central portion 78 dished downwardly and is here shown as having centrally fastened thereto in any suitable manner a stud having a threaded shank 79 cooperating with the wing nut 73. The stud 79 may be guided and positioned by an aperture 80 in a lug 81 joined integrally to the arcuate portion 35 of the support 27. The lower margins of the flanges 76, 77 may engage upper surfaces 82 of lugs projecting upwardly from the arcuate portion 35. In tightening up the wing nut 73, the upper surface of the nut engages the portion 68 of the reflector, adjacent the margin of the aperture 69 which is almost as large as the wing nut, the aperture 69 providing a free opening at the center of the reflector.

The resistor 50 within the element 22 is suitably connected to a pair of terminal studs 83, 84, and the resistor 50 of the element 21 is suitably connected to a pair of terminal studs 85, 86, all of these studs being desirably so located that they are disposed circumferentially between the arms 30, 31 when the elements are assembled with the support 27.

A suitable insulating conductor terminal connection block 87 may be provided, the block having separate chambers in which are disposed conductors 88, 89, 90. The conductor 88 is connected to the terminal stud 85; the conductor 89 is connected to the terminal stud 83; and the conductor 90 is connected to the terminal stud 84. The terminal stud 83 of the heating element 22 is connected to the terminal stud 86 of the heating element 21, by means of a conductor 91. In view of the fact that the heating elements 21, 22 are movable with respect to some fixed point, the conductors 88, 91 are desirably made flexible, and one way in which this may be done is to make these conductors of laminated form, the laminations being of desired thinness and number to secure the desired flexibility and conducting capacity. In Figure 2 one of the conductors, 91, is broken away to show its laminated construction.

The support ring 24 is here shown as comprising an annular generally horizontal portion 92, and at its outer periphery has a downwardly extending cylindrical flange 93, the lower margin of which is adapted to rest on the stove top 23. The inner periphery of the annular portion 92 has a downwardly extending generally cylindrical longer flange 94. The junction portions between the annular portion 92 and the flanges 93, 94 respectively are desirably rounded. The flange 94 is provided with three apertures 95, on the lower margins of which shoulders 96, provided on the frame 34, are adapted to rest, the construction and arrangement being such that when the support 27 and support ring 24 are assembled, the

upper surfaces of the heating elements 21, 22 are desirably somewhat above the top of the annular portion 92 of the support ring 24.

The usual practice in electric ranges is to have the uppermost surfaces of the heating element or elements define a fixed single plane. Such construction of course will give maximum propinquity between the heating surfaces and the surface of the part to be heated, provided the surface of the part to be heated is also a plane. Cooking vessels, however, irrespective of their original form, ordinarily do not satisfy that condition, some having the bottom thereof bulged outwardly and some bulged inwardly. In fact, some cooking vessels are originally made with the bottom slightly recessed in the central region. While these variations from a plane form are not great, it has been found that a relatively small air space between the bottom of a vessel and the surface of the heating element or elements materially slows down the heating speed, raises the temperature of the heating element and lowers the running efficiency of the element and also tends to shorten the life of the element.

It will be evident that if the heating elements are movably mounted, as hereinbefore described, that the upper surfaces of the heating elements will be adjusted to and adapt themselves to the surfaces of various types and forms of vessels placed thereon. For example, in case a vessel which has the central portion of the bottom thereof slightly recessed upwardly, is placed upon a range unit such as herein disclosed, the portion of the bottom of the vessel which surrounds the central recessed portion of the bottom will push downwardly on the upper surface of the element 21, thereby causing the saddles 39 to swing about their pivots and push the element 22 upwardly into contact with the central recessed portion of the bottom of the vessel. On the other hand, if the central portion of the vessel is bulged downwardly somewhat, the element 22 will be pushed downwardly, thereby causing the saddles 39 to swing and push the element 21 upwardly into contact with the outer part of the bottom of the vessel. It will be evident that the described construction and arrangement permits such swinging of the saddles 39 with respect to the heating elements. The downward movement of a heating element, from its position shown in Figure 3, is limited as hereinbefore described. The maximum relative movement of the heating elements 21, 22 is of course double the movement of one element in the illustrated embodiment. The aforesaid relative movement need be only slight to take care of substantially usual conditions.

From the foregoing it will be apparent that the saddles 39 serve to equalize the forces acting against the upper surfaces of the heating elements 21, 22. Accordingly, it will be further apparent that equalization will take place even though the forces acting on either of the elements are not uniformly circumferentially distributed. For example, the forces may be such as to move the element 21 downwardly at one place and to move it upwardly at another place, the unit 22 being correspondingly moved in respectively opposite directions at those places. This would occur if the bottom of the vessel is not bulged outwardly, or inwardly, uniformly.

Referring to the embodiment shown in Figures 5 through 8, a support 27a similar to the support 27 of the embodiment of Figure 2 is provided for supporting heating elements 21a, 22a. However, in this instance, no slots and fulcrums, such as

the slots 41 and fulcrums 43 of the embodiment of Figures 1 through 4 are provided in the arms 29a, 30a, 31a of the support 27a. The heating elements 21a, 22a are identical with the heating elements 21, 22 but the rivets 52a to 57a inclusive, are shorter than the rivets 52 to 57 inclusive, and the washers 97, provided on the rivets 52a to 57a, are spaced from and adapted (after predetermined movement) to engage the under side of the tops of the bushings 36a, 37a respectively.

As here shown, two levers or saddles 98, 99 are suitably pivoted, intermediate their ends, on machine screws 100, screwed into portions 101, 102, of the support 27a, which extend in a generally radial direction. Bottom surfaces of the heating elements 21a, 22a respectively rest on opposite end portions of the saddles 98, 99, as shown in Figure 7; and these saddles are so constructed and arranged that when a saddle is in the position shown in Figure 7, the tops of the heating elements are flush, and, consequently, as is apparent from Figure 6, either element 21a, 22a, may move downwardly a predetermined amount, as hereinbefore explained, thereby swinging the saddle and causing the other element to move upwardly at that saddle.

As here shown, two additional levers or saddles 103, 104 are provided, each having a V-shaped seat 105 intermediate its ends, as shown in Figure 8, these seats being adapted to rest on V-shaped fulcrums 106, 107 respectively, provided at the bottoms of notches 109 in the portions of the frame 34a between the arm 29a and the auxiliary arms 32a, 33a respectively. Each end of each of the saddles 103, 104 is here shown as provided with a generally cylindrical transversely extending portion 110. As may be seen from Figure 8, bottom surfaces of the heating elements 21a, 22a respectively rest on the end portions 110, the saddles 103, 104 being constructed and arranged to function as already stated in connection with the saddles 98, 99.

Referring now to the embodiment shown in Figures 9 and 10, a support 27b, similar to the support 27a of the embodiment of Figure 5, is provided for supporting heating elements 21b, 22b. These heating elements are associated with the support 27b in the same manner as are the heating elements 21a, 22a with the support 27a, that is, as shown in Figures 5 and 6. However, the support 27b differs from the support 27a shown in Figure 5 in that pivot rods 111, 112 are provided between the junctions of the bosses 36b, 37b of the arms 30b, 31b respectively, and the arcuate portion 113. Two other pivot rods 114, 115 are also here shown as provided between opposite sides respectively of the junction of the bosses 36b, 37b of the arm 29b and portions of the frame 34b between the arm 29b and the auxiliary arms 32b, 33b respectively. On each of these pivot rods, 111, 112, 114, 115, is swingably seated a saddle 116, such as shown in Figure 10. Each saddle 116 has a recess 117 with a rounded seat complementary to any of the pivot rods, and has a pair of upwardly extending fulcrum projections 118 on which bottom surfaces of the heating elements 21b, 22b respectively rest. Collars 119 may be provided on the pivot rods to hold the saddles 116 against longitudinal movement on the rods.

It will be evident that the embodiments respectively shown in Figures 5 through 8, and in Figures 9 and 10, will serve to adjust the surfaces of the heating elements to the surface of vessels placed thereon in a manner analogous

to that already described in connection with the embodiment of Figures 1 through 4.

From the foregoing it will be apparent to those skilled in the art that each of the illustrated embodiments of my invention provides a new and improved electric heater, and accordingly, each accomplishes the principal object of my invention. On the other hand, it also will be obvious to those skilled in the art that the illustrated embodiments of my invention may be variously changed and modified, or features thereof, singly or collectively, embodied in other combinations than those illustrated, without departing from the spirit of my invention, or sacrificing all of the advantages thereof, and that accordingly, the disclosure herein is illustrative only, and my invention is not limited thereto.

I claim:

1. Electric heating apparatus, comprising: a plurality of electrical heating elements; means mounting said heating elements for relative movement; and means so constructed and arranged that a force causing movement of one of said heating elements will positively cause movement of another of said elements.

2. Electric heating apparatus, comprising: a plurality of electrical heating elements; means mounting said heating elements for relative movement; and means so constructed and arranged that a force causing movement in a given direction of a part of one of said heating elements will cause movement in an opposite direction of an adjacent part of another of said elements.

3. Electric heating apparatus, comprising: at least two electrical heating elements; means constructed and arranged to movably mount said heating elements; and means, including a lever having a pivot intermediate its ends, so constructed and arranged that said heating elements are adapted respectively to engage said lever at opposite sides of said pivot.

4. Electric heating apparatus, comprising: at least two electrical heating elements; and means constructed and arranged to mount said heating elements with adjacent marginal portions thereof spaced to permit relative movement; and means, including a lever having a pivot intermediate its ends, said pivot being disposed approximately opposite the space between said elements, so constructed and arranged that said heating elements are adapted respectively to engage said lever at opposite sides of said pivot.

5. Electric heating apparatus, comprising: a plurality of heating elements having surfaces adapted for cooperation with a surface of a device to be heated, each of said heating elements being of annular form concentrically disposed; means mounting said heating elements for relative movement in the general direction of the common axis of said elements; and means so constructed and arranged that relative pressure between said heating elements and the device to be heated causes adjustment of said heating element surfaces with respect to the surface of the device to be heated.

6. Electric heating apparatus, comprising: a plurality of heating elements having surfaces adapted for cooperation with a surface of a device to be heated, each of said heating elements being of annular form and concentrically disposed; means mounting each of said heating elements for universal movement with respect to their common axis; and means so constructed and arranged that relative pressure between said

heating elements and the device to be heated causes adjustment of said heating element surfaces with respect to the surface of the device to be heated.

5 7. Electric heating apparatus, comprising: a plurality of heating elements having surfaces adapted for cooperation with a surface of a device to be heated; means mounting said heating elements for relative movement; and means, including a plurality of levers pivoted intermediate their ends and engageable at opposite sides of their pivots by certain of said heating elements, so constructed and arranged that relative pressure between said heating elements and the device to be heated actuates one or more of said levers to cause adjustment of said heating element surfaces with respect to the surface of the device to be heated.

20 8. Electric heating apparatus, comprising: a plurality of heating elements having surfaces adapted for cooperation with a surface of a device to be heated, each of said heating elements being of annular form concentrically disposed; means mounting said heating elements for relative movement in the general direction of the common axis of said elements; and means, including a plurality of levers pivoted intermediate their ends and engageable at opposite sides of their pivots by certain of said heating elements, so constructed and arranged that relative pressure between said heating elements and the device to be heated actuates one or more of said levers to cause adjustment of said heating element surfaces with respect to the surface of the device to be heated.

25 9. Electric heating apparatus, comprising: a plurality of heating elements having surfaces adapted for cooperation with a surface of a device to be heated, each of said heating elements being of annular form concentrically disposed; means mounting said heating elements for universal movement with respect to their common axis; and means, including a plurality of levers pivoted intermediate their ends and engageable at opposite sides of their pivots by certain of said heating elements, so constructed and arranged that relative pressure between said heating elements and the device to be heated actuates one or more of said levers to cause adjustment of said heating element surfaces with respect to the surface of the device to be heated.

40 10. An electric range unit, comprising: an electrical heating element; supporting means for said element, said supporting means having an aperture; and means, including at least one stud carried by said element and extending through said aperture, so constructed and arranged as to mechanically hold said heating element connected to said supporting means and permit limited relative movement of said heating element toward and away from said supporting means.

45 11. An electric range unit, comprising: a support; a heating element having a surface adapted for cooperation with a surface of a device to be heated, said element being movable with respect to said support; control means, including a part movably mounted on said support and serving to support said element, so constructed and arranged that relative pressure between said heating element and the device to be heated causes adjustment of said heating element surface with respect to the surface of the device to be heated; and positive stop means, including a part carried by said element and engageable with said control means, so constructed and arranged as to

limit movement of said element away from said support.

12. An electric range unit, comprising: a support; a heating element having a surface adapted for cooperation with a surface of a device to be heated, said element being movable with respect to said support; control means, including a lever pivoted on said support, so constructed and arranged that relative pressure between said heating element and the device to be heated causes adjustment of said heating element surface with respect to the surface of the device to be heated; and positive stop means, including a part carried by said element and engageable with said lever, so constructed and arranged as to limit movement of said element away from said support.

13. An electric range unit, comprising: a grid; a plurality of electrical heating elements disposed over said grid, said heating elements being relatively movable in a direction toward or away from said grid; and means so constructed and arranged that a force causing movement of one of said heating elements will thereby positively cause movement of another of said elements.

14. An electric range unit, comprising: a grid; a plurality of electrical heating elements disposed over said grid, said heating elements being relatively movable in a direction toward or away from said grid; and means so constructed and arranged that a force causing movement in a given direction of a part of one of said heating elements will thereby cause movement in an opposite direction of an adjacent part of another of said elements.

15. Electric heating apparatus, comprising: a plurality of electrical heating elements having surfaces for cooperation with a surface of a device to be heated; supporting means for said elements, said supporting means having apertures; means, including studs carried by said elements and extending through said apertures, so constructed and arranged as to mechanically hold said heating elements connected to said supporting means and permit limited relative movement of said heating elements toward and away from said supporting means; and means so constructed and arranged that relative pressure between said heating elements and the device to be heated causes adjustment of said heating element surfaces with respect to the surface of the device to be heated.

16. Electric heating apparatus, comprising: a plurality of electrical heating elements having surfaces for cooperation with a surface of a device to be heated; supporting means for said elements, said supporting means having apertures, means, including studs carried by said elements and extending through said apertures, so constructed and arranged as to mechanically hold said heating elements connected to said supporting means and permit limited relative movement of said heating elements toward and away from said supporting means; and means so constructed

and arranged that a force causing movement of one of said heating elements will thereby cause movement of another of said heating elements.

17. An electric range unit, comprising: a support having an aperture; a lever pivoted on said support, said lever having an aperture; a heating element having a surface adapted for cooperation with the surface of a device to be heated, said element being movably mounted with respect to said support and being engageable with said lever; and lost motion connection means between said element and said lever, said connection means including a stud carried by said element and extending through said apertures, and said connection means being so constructed and arranged that disengagement of said stud from said lever is prevented.

18. Electric heating apparatus, comprising: a plurality of relatively movable heating elements having surfaces adapted for cooperation with a surface of a device to be heated; supporting means for said elements, including a plurality of levers pivoted intermediate their ends and engageable at opposite sides of their pivots by certain of said heating elements, so constructed and arranged that relative pressure between said heating elements and the device to be heated actuates one or more of said levers to cause adjustment of said heating element surfaces with respect to the surface of the device to be heated.

19. Electric heating apparatus, comprising: a plurality of relatively movable heating elements having surfaces adapted for cooperation with a surface of a device to be heated; supporting means for said elements, including means, engageable by said elements, for transmitting pressure from one element to another; and said pressure transmitting means being so constructed and arranged that relative pressure between one of said heating elements and the device to be heated causes pressure to be transmitted through said pressure transmitting means to cause adjusting movement of another of said elements with respect to the device to be heated.

20. Electric heating apparatus, comprising: a support; a plurality of relatively movable heating elements having surfaces adapted for cooperation with a device to be heated; a plurality of levers pivoted intermediate their ends on said support, said levers having apertures; said heating elements and said levers being relatively so constructed and arranged that certain of said levers are engageable at opposite sides of their pivots by certain of said heating elements; and lost motion connection means between said certain elements and levers, said connection means including studs carried by said elements and cooperating with respective ones of said apertures, and said connection means being so constructed and arranged that disengagement of said studs from the respective said levers is prevented.

FRANCIS W. PERRY.
